PORTABLE, REVERSIBLE DANCE FLOOR

Herbert B. Mueller, Los Angeles, Calif.

Application March 6, 1953, Serial No. 340,791

2 Claims. (Cl. 20—6)

This invention relates to portable reversible dance flooring, and more particularly to a portable dance flooring provided with improved means for maintaining its connected parts dependably in place in the laid or operable position.

It is an object of the present invention to improve upon the portable dance floors which form the subject matter of Patents No. 2,019,692, and No. 2,102,086, respectively issued to me November 5, 1936, and December 14, 1937.

In said patented floor structures each floor section consists of boards or narrow strips which have to be secured together in the manufacture of the floor, and although they form a good floor, yet not so desirable a floor as that provided by the present invention.

My invention relates to a dual-surface interlocking portable floor, its principal use is to provide a decorative and practical resilient floor for dancing in the home.

The principal object of my invention is to facilitate a quick change of the surface design or pattern in a sectional movable dance floor, by the use of either surface or a combination of alternate surfaces in joining the sections together in the desired pattern.

Another object of my invention is to laminate a different design and/or colors on opposite sides of a section of Masonite or similar sheet material, and to provide a means for securely joining the sections together by turning a locking device from either side of a section.

A further object of my invention is to prevent the aforementioned floor from moving when laid over woven carpeting, by anchoring the same to the warp in the carpet. Dancing upon the portable, laid floor will cause it to "creep" in relation to the underlying carpet unless it is securely anchored to the latter.

A still further object of the present invention is to improve upon floors constructed of wood by providing novel plastic and steel structures to stiffen and strengthen the floor and to prevent its edge portions from breaking.

In carrying out the objects of the present invention square floor panels or sections are provided, which are securable to each other with their edges abutting in a floor forming assembly.

Other objects, advantages and features of invention will hereinafter appear.

Referring to the accompanying drawing, which illustrates a preferred embodiment of the invention,

Fig. 1 is a fragmentary plan view of a dance floor constructed in accordance with my invention, upper portions of the floor being broken away in four places so as to show structure that would be hidden. In this view six floor panels are completely shown, together with fragments of associated panels.

Fig. 2 is an enlarged, fragmentary vertical section on line 2—2 of Fig. 1.

Fig. 3 is an enlarged, fragmentary, horizontal section illustrating one of the locking devices. Line 3—3 of Fig. 4 indicates the plane of section.

2

Fig. 4 is a fragmentary vertical section on line 4—4 of Fig. 1.

Fig. 5 is a perspective view of one of the flanged clips which are used to prevent lateral displacement of the floor panels or sections.

Fig. 6 is a fragmentary sectional view of one of the panels illustrating the tongue and groove portions thereof.

Referring in detail to the drawing, this improved portable floor is therein shown as comprising an assembly 10 of inner square panels 11 and outer square floor panels 11, these panels all being constructed in substantially the same way, but different reference characters being applied to the outer panels from the inner ones for convenience in description.

15 By preference and as shown, each of these panels consists of a middle lamina 15, an upper plastic lamina 16, and a lower plastic lamina 17. Said middle lamina is preferably made of a tempered plastic, such as Masonite, and said upper and lower lamina are preferably made of "Vinol" or other, firm durable plastic substance having a smooth, hard outer finish.

In the laid floor said panels abut each other in an edge-wise manner, there being a tongue and groove fit between the abutting panels as best illustrated in Figs. 1 20 and 6. Said tongues and grooves occupy only about the central third of the width of the middle lamina, the tongues being formed by gluing, or otherwise securing, metal strips into the aforesaid grooves where desired.

In order to secure to each other the adjacent panels 30 of the laid floor, tool operable, swingable hooks 25 cooperate with vertical pins 26. Each of said hooks is provided with a tool socket 27 located at the axis about which the hook swings. These hooks need not be further described since they are substantially the same as 35 the hooks used for a similar purpose described in my aforesaid Patent No. 2,102,086.

In order to provide a clear operating space for each of said hooks 25 (each hook being located in an edge portion of a panel), the edge portion of the middle lamina 40 15 of the hook carrying panel is provided with a semicircular recess 30 and the adjacent panel edge is likewise provided with an opposed recess 31 formed by cutting away through somewhat more than a semicircle the edge portion of the middle lamina 15 of the adjacent tongue carrying panel. Each said pin 26, as shown in Fig. 4, extends through all three laminae of the panel which carries it, and each swingable hook 25 likewise has its bearings partly in the upper and lower lamina of the panel in which it is mounted.

50 Two types of anchor plates or clips are provided to hold the laid floor against "creeping" or lateral shifting. All of the panels (both 10 and 11), are held in part, inwardly spaced from their margins, by small anchor plates 35 which underlie the panels in the laid floor, pins 36 55 standing from said plates 35 and projecting upwardly into the panels. Each of said anchor plates is suitably perforated to receive a plurality of small pointed pins 37 which are so short that they do not reach the floor 39 which underlies the carpet 40, a suitable thin pad 41 60 being interposed between said carpet and floor. Said carpet is shown comprising a nap 40a which is sufficiently compressible to allow the thin anchor plates to embed themselves therein when the assembled panels are superimposed upon them.

65 Marginal anchor plates or clips 45 are also provided for the laid floor each of these plates having a flat, rectangular body portion 46 and across one end an upstanding channel forming flange or hook portion 47. The 70 channel or open side of the hook portion is directed toward the body portion of the plate and completely spans the edge portion of the portable floor. These anchor

plates have through their body portions a plurality of small apertures 48 to receive pins 49 like the aforesaid pins 37 and dimensioned to extend downwardly to the same extent.

Preparatory to putting the floor forming panels in place, straight marks may be made on the carpet indicating where the edges of the laid panel assembly will be located, and said marks then be used as guides for putting the floor in place. Clips 47 are placed under the edge of the floor after it has been laid, only on the sides in which direction the nap leans. Also plates 35 need not be placed in all sections, but are only used where needed to keep the floor from creeping. As the workman proceeds to put the various panels in place he will slip the pins 36 of the interior anchor plates through suitable perforations that have been provided for them in said panels, the anchor pins 37 having been previously projected into said plates 35 in a friction tight manner with their point portions projecting as shown.

As the laying of the floor proceeds the tongues 21 will be inserted into the grooves 20 with which they co-operate, and the hooks 25 (initially confined to the semi-circular recesses 30), will be swung by the use of a suitable tool into interlocking relation to the pins 26, thus securely locking together the adjacent panels of the laid floor.

When not in use the square panels 10 and 11, being all of the same size (desirably about three feet square), may be readily superimposed upon each other in pack form for storage or shipment.

Owing to the aforesaid grooves, tongues and locking hooks being located in the midwidth portion of the middle lamina, any one or more of the panels of the laid floor may be removed, and replaced in an inverted position, and thereupon locked into place. Also, owing to the

panels being square, one or more of them may be removed from the laid and replaced after being given one or more quarter turns.

I claim:

5 1. The combination, with a portable laid floor, of angular clips having elongated horizontal body portions and upstanding from end portions of said body portions hook portions abutted internally by and completely spanning marginal portions of said floor, and pins extending through said body portions into an underlying carpet, said pins terminating superjacent to the floor upon which the carpet rests, so that the floor under the carpet is unmarred by said pins.

15 2. The combination, with a portable laid floor, a carpet upon which said floor is superimposed, and a permanent floor underlying said carpet; of horizontal anchor plates between said floor and carpet, and fastening means securing said plates both to said portable floor and to said carpet, said fastening means having point portions terminating superjacent to the permanent floor.
